UNITED STATES PATENT OFFICE.

BENTON G. DOSCH AND FRANK C. SAWHILL, OF ALLEGHENY, PENNSYLVANIA.

ATTACHMENT FOR GAS-STOVES.

SPECIFICATION forming part of Letters Patent No. 410,504, dated September 3, 1889

Application filed August 10, 1887. Renewed February 19, 1889. Serial No. 300,493. (No model.)

To all whom it may concern:

Be it known that we, BENTON G. DOSCH and FRANK C. SAWHILL, both residents of Allegheny, in the county of Allegheny and State of Pennsylvania, have invented certain new and useful Improvements in Attachments for Gas-Stoves; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of our improved attachment for gas-stoves, showing the same in its operative position; and Fig. 2 is a central transverse vertical sectional view of the same.

The same letters of reference indicate corresponding parts in both figures.

Our invention consists in a new and improved attachment for cook-stoves using natural gas for fuel, which will be hereinafter fully described and claimed.

Referring to the several parts by letter, A indicates the top plate of our attachment for gas-stoves, which may be formed either perfectly solid or with openings B B and lids C C for the same, which lids may be turned back or removed entirely when desired.

To place our improved attachment in position in a cook-stove using gas, the lids and the cross-bar between the same are removed from the front of the stove and the attachment placed in position in the front of the stove, with edges or flange A' of the top plate A resting upon the top of the stove proper, and to the forward part of this top plate is rigidly secured the front plate D, which may be made of any desired length to protect the front of the stove from heat, and which is preferably made of such a length that its lower edge rests upon the grate of the stove.

To the back of the top plate A is hinged at its upper longitudinal edge the longitudinal damper E, and in the back of the top plate is arranged the lever or handle F for raising or lowering the damper. The upper end of this handle extends over the top of the top plate A, so that the damper can be adjusted from the outside, and the lower end of the handle

is provided with a horizontal arm F', which engages with the damper and swings it back into a horizontal position as the handle is turned one way or the other by means of the portion F. In place of this form of adjusting-handle, however, the lever or handle may have its outer end extended over to the side of the attachment, so that the damper can be adjusted from the side of the stove, as will be readily understood.

The attachment is placed in position in the forward part of the gas-stove over the perforated pipes which furnish the gas to the stove, so as to inclose or extend over the flames, with the lower edge of the longitudinal front of the attachment resting down upon the grate, and the edge flange of the top plate A resting upon the top of the stove, while the lower edge of the damper, when the latter is down in its lowermost position, will rest upon the forward edge of the top of the bake-oven G of the stove, as shown in the drawings, when it will be seen that the heat will be confined to the front part of the stove—to the attachment, in fact—while the rear part of the stove remains comparatively cool, thus enabling a person to do a great deal of cooking with considerable less fuel than would otherwise be necessary. As the heat is confined almost entirely to the attachment itself, its use does away with the intense heat in the kitchen caused by a hot stove, the stove proper remaining comparatively cool, and as soon as the cooking is completed and the gas turned off the stove will be entirely cool in a short time, as the attachment can be removed from the stove as soon as the gas is turned off. The damper, which prevents the heat from penetrating to other parts of the stove, can be opened and shut as desired from the outside by means of its adjusting-handle F, so as to cut the heat off entirely from the rear of the stove or admit a part thereof to escape from the attachment when desired.

The attachment, which is in the form of an inverted box or hood, may be constructed of any light thin metal—such as sheet or cast iron, zinc, or copper—and may be made with or without top holes in the top plate A and lids for the same. The end pieces I I of the attachment can be recessed at their lower

edges, as shown in dotted lines in the drawings, to adapt them to fit over the gas-pipe.

Having thus described our invention, what we claim, and desire to secure by Letters Patent of the United States, is—

The combination, with an attachment for gas-stoves, consisting of an inverted box or hood, of a longitudinal damper hinged at its upper edge to the back of the top plate of the attachment, and a handle in the back of the top plate, the lower end of which is provided

with a horizontal arm adapted to engage with the damper when the upper end of the handle is operated.

In testimony that we claim the foregoing as our own we have hereunto affixed our signatures in presence of two witnesses.

BENTON G. DOSCH.
FRANK C. SAWHILL.
